UNITED STATES PATENT OFFICE.

NOEL C. JONES, OF AUBURN, NEW YORK.

ICE-CREEPER.

SPECIFICATION forming part of Letters Patent No. 278,337, dated May 29, 1883.

Application filed October 11, 1882. (No model.)

To all whom it may concern:

Be it known that I, NOEL C. JONES, a citizen of the United States, residing at Auburn, in the county of Cayuga and State of New York, have invented a new and useful Ice-Creeper, of which the following is a specification, reference being had to the accompanying drawings.

Figure 1 is a perspective view of my improved ice-creeper. Fig. 2 is a side view, showing the same attached to a shoe; and Fig. 3 is a bottom plan view.

Corresponding parts in the several figures are denoted by like letters of reference.

This invention relates to ice-creepers; and it consists in certain improvements in the construction of the same, which will be herein-after fully described, and particularly pointed out in the claim.

In the drawings hereto annexed, A represents the body of my improved ice-creeper, which consists of a heel-plate, B, sole-plate C, and connecting-shank D, the whole cast or otherwise suitably formed in a single piece of malleable iron, or any other suitable material.

The heel-plate B and sole-plate C are forked or bifurcated longitudinally, as shown at E, which is in order to render the device light and elastic to the tread, and thus more effective.

The sides of the heel and sole plates are provided with upward-projecting lugs F, fitting against the edge of the sole of the shoe or boot to which the device is attached. The said heel and sole plates are also provided with downward-projecting sharp points G for the purpose of catching in the sleet or ice, and thus preventing the wearer from slipping and falling. The shank D has a longitudinal vertical slot, I, under which it is provided with

a longitudinal brace, J, between which and the body of the shank a strap, K, may be passed

for the purpose of attaching the device to the foot of the wearer.

The operation and advantages of my invention are obvious. It is exceedingly simple, 45 and may be manufactured at a trifling expense. It may be made in different sizes to fit the boots or shoes of men, women, or children, and it may be attached to or removed from the foot in a moment's time. It is valuable 50 and useful not only for ordinary use in winter, but especially, also, for the use of ice-men and lumber-men, and others whose pursuits are of a like nature.

I am aware that ice-creepers have been heretofore made consisting of variously-shaped frames having upward-projecting lugs fitting against the sides of the sole, and downward-projecting barbs or points. This, therefore, I do not claim; but I am not aware that ice-creepers have been constructed, as herein described, in a single piece with bifurcated heel and sole plates, whereby lightness and elasticity to the tread are insured. 55

I claim and desire to secure by Letters Patent of the United States—

The herein-described improved ice-creeper, consisting of the bifurcated heel and sole plates B C, connected by and cast or formed in a single piece with a shank, D, having slot 70 I and brace J to receive the strap K, said heel and sole plates being provided with upward-projecting lugs F, and with downward-projecting points or barbs G, as and for the purpose set forth.

In testimony that I claim the foregoing as my own I have hereto affixed my signature in presence of two witnesses.

NOEL CLEMENT JONES.
